R. A. WILSON.
WELL TUBING CATCHER.
APPLICATION FILED NOV. 3, 1920.

1,411,599.

Patented Apr. 4, 1922.

UNITED STATES PATENT OFFICE.

ROBERT A. WILSON, OF DALLAS, TEXAS, ASSIGNOR TO GUIBERSON CORPORATION, OF DALLAS, TEXAS, A CORPORATION OF DELAWARE.

WELL-TUBING CATCHER.

1,411,599.

Specification of Letters Patent.

Patented Apr. 4, 1922.

Application filed November 3, 1920. Serial No. 421,467.

To all whom it may concern:

Be it known that I, ROBERT A. WILSON, a citizen of the United States, residing at Dallas, in the county of Dallas and State 5 of Texas, have invented certain new and useful Improvements in Well-Tubing Catchers, of which the following is a specification.

This invention relates to new and useful improvements in well tubing catchers.

10 The invention has particularly to do with that type in which the gripping means, while the tubing is intact, are normally inoperative, but which due to the inertia of an associated weight and a pneumatic action, 15 is thrown into functional action when the tubing breaks.

15 The object of the invention is to provide pneumatic means normally under compression, but arranged to expand and operate the 20 gripping means when the tubing breaks; and involves the use of weight plungers and air cushions in lieu of the springs commonly employed.

An apparatus designed to carry out the 25 invention will be hereinafter described together with other features of the invention.

The invention will be more readily understood from a reading of the following specification and by reference to the accompanying drawings, in which an example of the 30 invention is shown, and wherein:

Fig. 1 is a vertical sectional view of a well casing showing a tubing catcher therein, constructed in accordance with my invention, the catcher being in vertical section,

35 Fig. 2 is a cross-section on the line 2—2 of Fig. 1,

Fig. 3 is a cross-section on the line 3—3 of Fig. 1, and

40 Fig. 4 is a cross-section on the line 4—4 of Fig. 1.

All the cross-sections are enlarged with respect to Fig. 1.

In the drawings the numeral 10 designates the well casing. The catcher involves 45 a section of well tubing 11 having an integral collar 12 at its lower end receiving the upper screw-threaded end of a lower section of tubing 13, however, the manner 50 of connecting the sections of tubing, is unessential. A gripper slip carrying head 14 has a central bore or passage 15 receiving at its lower end, the upper screw-threaded end of the section 11. The lower end of 55 an upper section of tubing 16 is screwed

into the upper end of the bore. It is obvious that the sections 11 and 16 and the head might be united in any suitable manner.

Gripper slips 17, of which three are shown, 60 but of which the desired number may be used, are formed on their outer faces with the usual teeth 18. These slips may be suitably mounted and I have shown each carried on a dove-tail slide 19 located vertically 65 at the center of an inclined boss 20. Three of these bosses are shown and they converge downwardly. The surfaces of the bosses are substantially flat and the inner faces of the slips are shaped to slide thereon. The 70 usual water courses or sumps 21 are located between the bosses.

At the base of each boss a shoulder or ledge 22 is provided and each shoulder functions as a stop or rest for receiving the slip 75 of its respective boss, whereby the downward displacement of the slips is arrested. The slips when resting on the shoulders, which form part of the head, will be inactive and their teeth 18 will be within 80 the diameter of said head. In order to sustain the slips and operate the same, links 23 are suitably pivoted in the lower ends of the slips and depend through slots 24 in the shoulders. The links have their lower ends 85 pivoted in a collar 25, slidably confined on the tubing section 11. The parts which have been enumerated and described up to this point are well known in this art and are capable of a wide variance in construction; 90 therefore, they are secondary to the improvement involved herein and merely contribute to the operation of the catcher.

Below the collar 25 a spider or ring 26 is slidably confined on the section 11 and 95 includes radial lugs 27. Plungers 28 have their upper ends provided with upstanding studs 29 penetrating the lugs and receiving nuts 30, whereby said plungers are suspended from the spider. The plungers are preferably cylindrical and solid so as to give them weight. The spider and plungers constitute a weight which owing to its inertia will momentarily remain suspended when the tubing breaks.

105 This is accentuated by means of cylinders 31 carried by the tubing section 11 in which the lower ends of the plungers are received. The plungers have a snug fit in the cylinders and the latter are suitably mounted on the 110

section 11, as by forming integral therewith. The plungers will compress the air in the cylinders and thus remain supported on air cushions. In such position the spider 26
5 will be slightly below the collar 25 when the slips are at rest on the shoulders 22. It will be seen that the slight vibrations of the plungers incidental to the manipulation of the
10 catcher, will be absorbed by the air cushions in the cylinders.

If the tubing should break the following action would be had. The inertia of the weight constituted by the plungers 28 and spider 26, accentuated by the expansion of
15 the compressed medium in the cylinders 31, will cause the contact of the spider with the collar 25. This engagement will result, through the agency of the links 23, in momentarily arresting and sustaining the grip-
20 per slips 17. The head 14 and the tubing sections being attached to the line of tubing will tend to descend more rapidly, consequently the inclined faces of the bosses 20 will ride down the inner faces of the slips 17,
25 and the latter will be displaced outwardly, whereby their teeth 18 will bite into the casting and hold the line of tubing against a further drop.

What I claim, is:

- 30 1. In a well tubing catcher, a tubing section, a head connected with the section, gripper slips mounted on the head, the head having inclined surfaces engaged by the slips, whereby the slips undergo an outward displacement when the head is displaced longitudinally, a sustaining element slidably mounted on the section and connected with the slips, a weight slidably mounted on the tubing section, and air cushion means nor-
35 mally supporting said weight.
2. In a well tubing catcher, a tubing section, a head connected with the section, gripper slips mounted on the head, the head having inclined surfaces engaged by the slips,
45 whereby the slips undergo an outward displacement when the head is displaced longitudinally, a sustaining element slidably mounted on the section and having support-
ing connection with the slips, a weight slid-
ably mounted on the tubing section, and pneumatic means carried by the tubing sec-
50

tion co-acting with the weight for holding the weight in suspension to be engaged by the slip sustaining element when the tubing breaks.

55

3. In a well tubing catcher, a tubing section, a head connected with the section, gripper slips mounted on the head, the head having inclined surfaces engaged by the slips, whereby the slips undergo an outward displacement when the head is displaced longitudinally, a sustaining element slidably mounted on the section and having supporting connection with the slips, a weight element slidably mounted on the tubing section, 60 a plunger weight carried by the weight element, and an air compression chamber carried by the tubing section and receiving the lower end of the plunger weight.

65

4. In a well tubing catcher, a tubing section, a head connected with the section, gripper slips mounted on the head, the head having inclined surfaces engaged by the slips, whereby the slips undergo an outward displacement when the head is displaced longitudinally, a sustaining element slidably mounted on the section and having supporting connection with the slips, a weight element slidably mounted on the tubing section, a plurality of plungers carried by the weight element, and a plurality of air compression cylinders carried by the tubing section and receiving the plungers.

70

5. In a well tubing catcher, a tubing section, a head connected with the section, gripper slips mounted on the head, the head having inclined surfaces engaged by the slips, whereby the slips undergo an outward displacement when the head is displaced longitudinally, a collar slidably mounted on the tubing section, links pivoted to the collar having their upper ends pivoted to slips, a spider slidably mounted on the tubing below the collar, a plurality of cylindrical solid plungers suspended from the spider parallel to the tubing section, and air compression cylinders mounted on the tubing section in fixed relation thereto and receiving the lower ends of the plungers.

75

In testimony whereof I affix my signature. 80

ROBERT A. WILSON.
